UNITED STATES PATENT OFFICE.

WILLIAM H. FOX AND HARLAN G. RICHEY, OF BLUFFTON, INDIANA.

FARM-GATE.

SPECIFICATION forming part of Letters Patent No. 341,840, dated May 11, 1886.

Application filed March 3, 1885. Serial No. 157,660. (No model.)

To all whom it may concern:

Be it known that we, WILLIAM H. FOX and HARLAN G. RICHEY, of Bluffton, in the county of Wells and State of Indiana, have 5 invented certain new and useful Improvements in Farm-Gates; and we do hereby declare the following to be a full, clear, and exact description of the invention, such as will enable others skilled in the art to which it 10 pertains to make and use the same.

Our invention relates to improvements in farm-gates; and it consists in certain features of construction and in combination of parts hereinafter described, and pointed out in the 15 claims.

In the accompanying drawings, Figure 1 is a view in perspective of our improved gate closed. Fig. 2 is a view in perspective of the gate opened. Fig. 3 is a view in perspective 20 of the cross-head and connecting-rods.

A represents the gate, provided with the track or way a, one portion of which is inclined, preferably as shown. The gate has an arm, A', extending rearward, that supports 25 the track a'. The track a travels on the roller b, supported from the post B, and the track a' passes between the rollers e e, supported from the post C. The shape and arrangement of these tracks are such that the gate, as it is 30 opened, is raised more or less from the ground, according as the tracks are inclined more or less, and these inclines may be arranged to raise or lower the gate at any part of its throw.

35 E is a post with a groove, e', having undercut edges, that form ways for the cross-head F to slide in. The edges of the cross-head are beveled to correspond to the shape of the ways, and the cross-head has a wrist, f, to 40 which is attached the connecting-rod G, the lower end of which is pivoted to the gate at g.

H are rods pivoted to the cross-head at f', and are connected at the upper ends, respectively, at h, by loops or in any suitable manner, 45 to the levers I. These levers are fulcrumed, respectively, at i to the cross-bar J, that is secured to the post B. The outer ends of the levers I have depending rods I', provided with rings, loops, or other convenient device for 50 grasping with the hand, and these handles are located so that they are conveniently operated from a carriage or by a person on foot.

The operation of the device is as follows: When the gate is closed, the position of parts is approximately shown in Fig. 1, and by 55 drawing down on one of the rods, I, the opposite end of the lever I will be raised, which, by means of the attachments shown, will raise the cross-head and cause the attached rod G to draw back on the gate or open it. The arrangement of parts is such that while the cross-head is at the top of its stroke and the rod G vertical the gate will have traveled half its throw. At this point, applying power 60 to the cross-head, either up or down, would 65 not move the gate in either direction, and to prevent the gate from stopping at this dead-point we have provided a double incline on the track a, located so that the depending point O will be over the roller b just as the dead-point of the connecting-rods is reached. The 70 gate would not be likely to stop with this point O on the roller b, and if the gate has sufficient momentum to carry it past the dead-centers, by pressing upward on the handle, 75 additional power may be applied to carry the gate to the end of its route, either open or closed, as the case may be.

Owing to the weight of the cross-head and 80 to the angular or bracing position of the connecting-rod G when the gate is closed or wide open, it is held quite firmly, and is not easily moved, except by drawing on the rods I', as aforesaid, and consequently the gate requires 85 no other fastening to keep it open or closed.

Usually in operating the gate a strong pull 90 on one of the handles will give the gate momentum enough to carry it to the opposite terminus without having to push up on the handle.

The gate is simple, durable, and convenient, and may be made at a small initial cost and of material that almost any farmer has at hand. Even the rollers may be of wood, and if of suitable hard wood will last a long time. 95

What we claim is—

1. The combination, with two posts located a distance apart, each having a roller, of a sliding gate having two curved tracks located in different horizontal planes, one of said 100 tracks extending from one end of said gate to the other end, and the other track projecting from the rear end of the gate, the said parts being arranged substantially as described, for

the purpose of permitting the gate to move longitudinally a distance equal to its length.

2. The combination, with two posts located a distance apart, each post being provided with a roller, and a sliding gate having two tracks, curved substantially as described, one of said tracks projecting from the rear end of the gate, the said rollers and tracks being arranged substantially as described, whereby 10 the curved portions of the tracks engage the rollers simultaneously, of the vertically-movable cross-head, the grooved post in which the cross-head rests and moves, a rod connecting the gate and cross-head, and operating- 15 levers connected to said cross-head, substantially as set forth.

3. The combination, with two posts, each

having a roller thereon, of a sliding gate, the two tracks located in different horizontal planes, one of said tracks extending from one end of the gate to the other, and provided with the double incline O, and the other track projecting from the rear end of the gate, for the purpose of permitting the gate to move longitudinally a distance equal to its length, 20 substantially as set forth. 25

In testimony whereof we sign this specification, in the presence of two witnesses, this 27th day of September, 1884.

WILLIAM H. FOX.
HARLAN G. RICHEY.
